Patented Sept. 2, 1913.

UNITED STATES PATENT OFFICE.

EDWARD LYMAN MUNSON, OF THE UNITED STATES ARMY.

APPARATUS FOR APPLYING DISINFECTANTS AND DEODORANTS.

1,072,351.

Specification of Letters Patent.

Patented Sept. 2, 1913.

Application filed August 17, 1912. Serial No. 715,663.

To all whom it may concern:

Be it known that I, EDWARD L. MUNSON, major, Medical Corps, United States Army, a citizen of the United States, residing at 5 New Haven, in the county of New Haven and State of Connecticut, have invented certain new and useful Improvements in Apparatus for Applying Disinfectants and Deodorants; and I do hereby declare the following to be a full, clear, and exact description of the invention, such as will enable others skilled in the art to which it appertains to make and use the same.

My invention relates to improvements in 15 an apparatus for the use of disinfectants and deodorants, and it consists of certain novel features that will be hereinafter described and claimed.

It is well known that with the present 20 mode of applying disinfectants and deodorants, in which the articles to be disinfected or deodorized are contained in a chamber, vessel, or box having fixed walls, and inclosing air under normal atmospheric pressure, the disinfecting or deodorizing gases 25 when injected into this atmosphere contained in the chamber mingle with the air and are largely diluted and weakened in efficiency thereby. This objection is in certain 30 instances remedied, at considerable trouble and expense, by the use of vacuum chambers, from which the air is exhausted before the disinfectant gas is let in.

According to my invention, I use a portable 35 generating apparatus for generating the disinfecting or deodorizing gases at the time and place required, and this portable apparatus is preferably made of such size and shape that it may be inclosed in a collapsible bag containing the articles to be treated, and the gas issuing from the apparatus forms a 40 strong gaseous mixture which inflates the bag as the gas is generated. Furthermore, the chemicals used are such as to generate the gas at sufficiently high temperature, and 45 containing a sufficient amount of aqueous vapor, which vapor condenses upon the articles treated and serves to insure the efficient action of the gas, which it carries down in water solution upon the infectious matters.

My invention will be understood by reference to the accompanying drawings, in which the same parts are indicated by the same numerals throughout the several views.

Figure 1 shows a central vertical section

through the apparatus, parts being shown in elevation and parts broken away; Fig. 2 shows a section through the apparatus along the line 2-2 of Fig. 1, and looking down; 60 Fig. 3 shows the apparatus as used in a collapsible bag containing the articles to be treated; and Fig. 4 shows the apparatus used outside a room for forcing the generated gas into a closed space. 65

1 represents an outer containing vessel, which we will call the container, which is closed by a cover 2, having a hollow cylinder 3 attached thereto, projecting downward into the container and forming a gas bell. This 70 top 2 is detachably connected to the container in any convenient way, as by screw threads 4, and is made suitably gas tight as by a gasket 5 of rubber, leather, or the like. Mounted in the bell is a mixing chamber 6, 75 which is also preferably cylindrical and which is supported above the base of the container and centered in any convenient way, as by means of the legs 7 which project down into the hollow supports 8, projecting above 80 the bottom of the container. I preferably provide three of these supports, two hollow, as at 8, and the other solid, as at 8^a, the three being arranged in triangular relation so that the bottom of the mixing chamber may be held a suitable distance above 85 the bottom of the container, and at the same time the container may be centered and held in fixed relation with regard to the dosing box, as will be hereinafter described. Mounted 90 in the upper end of the mixing chamber 6 is said dosing box 9, which is preferably in cylindrical form, and is provided with a hinged bottom 10 normally held in place by the spring clip 11, but which may be pressed 95 downward releasing said bottom and dumping the contents thereof into the mixing chamber. This dosing box is detachably mounted in the mixing chamber in any convenient way, but in order that it may always 100 be in the proper relation with regard to the tripping device for the bottom thereof, I preferably provide three pins 12 engaging in notches in the upper end of the mixing chamber, and provided with heads 13, and a 105 fourth pin 12^a, which is not provided with a head but passes through a hole in the shell of the mixing chamber whereby the parts cannot be assembled except when in the proper angular relation.

Mounted above the free end of the bottom 110 10 of the dosing box is a spring plunger 14

passing through a screw-threaded sleeve 15, 5 screwed in the cover 2 and kept gas-tight by a set collar 16 on the plunger, and a gasket 17 between said collar and said sleeve. The pressure of the gases will tend to keep this joint tight, as will also the action of the restoring spring 18, which tends to return the 10 spring plunger 14 to the initial position. This spring plunger is preferably provided with a head 19 for convenience in manipulation.

Connected to the container 1 are one or more nozzles 20 with gas passages 21 controlled by cocks 22 and 22^a. I preferably 15 provide two of these nozzles and cocks, so that one may be left permanently open if desired, and thus serve as a safety vent to prevent the apparatus from exploding should the pressure of the gases contained 20 therein become too great. For such reason, the cock 22^a preferably has no thumb piece and can only be turned by pliers, or with some difficulty. Should it be desired, of course, either or both of the cocks can be 25 closed or opened. One or both of these nozzles may be provided with a tube of rubber, or the like, 23 for carrying the gases generated to the point of delivery.

The use of the device in practice is as follows: Any suitable liquid, such as formalin, 30 is placed in the bottom of the mixing chamber 6, the level of such liquid being indicated by the dotted lines 25 in Fig. 1. Above the bottom 10 in the dosing box any suitable 35 granular reagent 26 is placed, such as permanganate of potash, calcium carbid, quick lime, or the like. The parts being assembled in the position shown in Fig. 1, the top being sealed, the cock 22^a being opened and the 40 cock 22 being closed, by pushing down on the head 19 of the plunger, the bottom 10 of the dosing box will be released from the catch 11, and it will fall to the position indicated in dotted lines in Fig. 1, the granular 45 contents dropping into the liquid in the bottom of the container and the gas generated or liberated by the heat of the reaction will rise upward in the mixing chamber and then pass downward inside the gas bell 3, and finally up through the annular 50 space between the gas bell and the container and out through the open cock 22^a. If it be desired, both cocks may be left open, in which event gas will flow through both 55 cocks. The gas generated will be heated by the chemical reaction and will also carry along with it considerable aqueous vapor, which aqueous vapor will condense on the articles to be treated when the gas becomes 60 cooled sufficiently, thus furnishing the necessary moisture for the efficient action of the disinfectant or deodorant in protoplasm. By using a strong concentration of gas, at 65 a high temperature and saturated with moisture, the gas penetrates rapidly into all parts

of the fabric, displacing the air, carrying with it a large amount of moisture which, as the temperature falls, dissolves a part of the gas and carries it down to form a thin watery film over the infectious material, 70 which is thereby acted on much more effectively. By having the hot gas and aqueous vapor pass down beneath the bottom edge of the gas bell 3, any drops of liquid and solid matters thrown off by the violent ebullition of the chemicals will drop into the bottom of the container, and only the gas and aqueous vapor in suspension will pass upward and find its exit through the nozzles. As considerable heat may be engendered during the operation of the device, the bottom of the mixing chamber is preferably spaced away from the bottom of the container, as shown, so that the articles being treated may not be subjected to excessive 75 heat.

This apparatus is especially useful for treating baggage, or clothing in small quantities, in which case the baggage, or clothing to be treated is placed in a collapsible bag 27 (see Fig. 3), the apparatus is placed in the bag together with the articles to be treated, the air, as far as practicable, is pressed out of the bag, and the open end of the bag is sealed up. The plunger is 90 then pressed downward from the outside of the bag after the bag has been sealed. In such instances, it is preferable to have both cocks open so that the gases generated may disseminate from two directions through the 95 articles to be treated, and the bag with the clothing, gas, and apparatus therein may be left sealed for an indefinite period, or it may be opened after an adequate time interval 100 has elapsed. Suitable bags for this purpose would be the rubber bags made of rubber sheeting or the ponchos used by soldiers, bags made of heavy paper, or other bags especially manufactured for the purpose. It 105 will be obvious that if large articles, such as mattresses are to be treated, large bags of special construction may be used. It will also be obvious that the portable apparatus may be placed in the bottom of a trunk among the articles to be disinfected, and the 110 trunk closed, or it may be placed in an ice chest, refrigerator, cellar, or other room, box, or receptacle where the processes of disinfecting or deodorizing are desired. The apparatus may also be used outside them to 115 disinfect closed rooms, or the contents of rigid or flexible containers, as shown in Fig. 4, where the container 1 is connected to the key-hole of a door by the tube 23.

It will be obvious that the apparatus may 120 be made in varying sizes to suit the requirements, thus for treating the individual outfit of a soldier or sailor, a small container about the size of a half gallon cup will be sufficiently large, while where it is desired to 125

treat large chambers, or other receptacles, a large size of apparatus may be used.

I do not claim to have discovered any special chemical reagents, whereby the gases for disinfecting or deodorizing may be generated, as these are well-known in the art. The apparatus is adapted to generate a great variety of such disinfecting or deodorizing gases, the fundamental principle being that the two reagents for generating the gas are held in the same vessel, but separated, until the moment it is desired to generate the gas, then the two reagents are brought together, and the gases generated and delivered as desired.

It will be obvious that various modifications might be made in the herein described apparatus and in the construction, combination and arrangement of parts which could be used without departing from the spirit of my invention.

Having thus described my invention, what I claim and desire to secure by Letters Patent of the United States is:

1. A disinfecting and deodorizing apparatus comprising a readily collapsible and inflatable envelop; a containing vessel associated with said envelop; a mixing chamber mounted in said containing vessel and adapted to contain liquid; a dose box located above the bottom of said mixing chamber adapted to contain chemical reagents; with means adapted to be operated from the exterior of said container envelop for dumping the contents of said dose box into said liquid; and means for conducting the gases generated in said container to the interior of said envelop, substantially as described.

2. A disinfecting and deodorizing apparatus comprising a containing vessel, a mixing chamber mounted therein and adapted to contain liquid, means for centering and supporting said mixing chamber from the bottom of said containing vessel, a dose box located above the bottom of said mixing chamber adapted to contain chemical reagents in granular form, with means operated from the exterior of said container for dumping the contents of said dose box into said liquid, comprising a spring plunger projecting through the cover of the container, and a yielding bottom mounted in said dose box and adapted to be released by said spring plunger, and means for carrying off the gases generated from said container, substantially as described.

3. A disinfecting and deodorizing apparatus comprising a containing vessel, a mixing chamber mounted therein and adapted to contain liquid, means for centering and supporting said chamber above the bottom of said containing vessel, a dose box located above the bottom of said mixing chamber adapted to contain a chemical reagent, with means operated from the exterior of said

container for dumping the contents of said dose box into said liquid, a detachable cover mounted on said container and provided with a downwardly projecting shell forming a gas bell, and means for carrying off the gases generated from said container, substantially as described.

4. A disinfecting and deodorizing apparatus comprising a containing vessel, a mixing chamber mounted therein and adapted to contain liquid, means for centering and supporting said chamber above the bottom of said containing vessel, a dose box located above the bottom of said mixing chamber adapted to contain chemical reagents in granular form, with means operated from the exterior of said container for dumping the contents of said dose box into said liquid, comprising a spring plunger projecting through the cover of the container, and a yielding bottom mounted in said dose box and adapted to be released by said spring plunger, a detachable cover mounted on said container and provided with a downwardly projecting shell forming a gas bell, and means for carrying off the gases generated from said container, substantially as described.

5. A disinfecting and deodorizing apparatus comprising a cylindrical containing vessel, a cylindrical mixing chamber mounted therein and adapted to contain liquid, means for centering and supporting said chamber above the bottom of said containing vessel, a dose box located above the bottom of said mixing chamber adapted to contain a chemical reagent, with means operated from the exterior of said container for dumping the contents of said dose box into said liquid, a detachable cover mounted on said container and provided with a cylindrical shell forming a gas bell projecting downwardly between said mixing chamber and said container, and means for carrying off the gases generated from said container, substantially as described.

6. A disinfecting and deodorizing apparatus comprising a containing vessel, a mixing chamber mounted therein and adapted to contain liquid, means for centering and supporting said chamber above the bottom of said containing vessel, a dose box supported from the top of said mixing chamber adapted to contain a chemical reagent, and provided with a yieldingly sustained hinged bottom, a spring plunger operated from the exterior of said container for releasing said bottom and dumping the contents of said dose box into said liquid, a detachable cover mounted on said container and provided with a shell forming a gas bell projecting downward between said mixing chamber and said container, and means for carrying off the gases generated from said container, substantially as described.

7. A disinfecting and deodorizing apparatus comprising a containing vessel, a mixing chamber mounted therein and adapted to contain liquid, means for centering and supporting said chamber above the bottom of said containing vessel, a dose box supported and centered at the top of said mixing chamber adapted to contain a chemical reagent, with means operated from the exterior of said container for dumping the contents of said dose box into said liquid, a

gas bell interposed between said container and said mixing chamber, and means for carrying off the gases generated from said container, substantially as described. 15

In testimony whereof, I affix my signature, in presence of two witnesses.

EDWARD LYMAN MUNSON.
